S. WEISS.
PICTURE FRAME.

APPLICATION FILED NOV. 20, 1919.

1,356,575.

Patented Oct. 26, 1920.

INVENTOR
Simon Weiss,
By Frederick V. Winters, Attorney

UNITED STATES PATENT OFFICE.

SIMON WEISS, OF NEW YORK, N. Y.

PICTURE-FRAME.

1,356,575.

Specification of Letters Patent. Patented Oct. 26, 1920.

Application filed November 20, 1919. Serial No. 339,471.

To all whom it may concern:

Be it known that I, SIMON WEISS, a citizen of the United States, and resident of New York, in the county of Bronx and 5 State of New York, have invented certain new and useful Improvements in Picture-Frames, of which the following is a full, clear, and exact specification.

This invention relates to picture frames, 10 and has for one of its objects to provide an improved form of rigid back member and simplified means for detachably securing said back member bodily to the frame.

Another object is to provide improved 15 means of securing a prop to the back member so that the extending of the prop will not tend to loosen its connection with said back member. A further object is to provide improved means for attaching a 20 hanger ring to the back member independently of the frame. Still another object is to provide simplified means for fastening the glass in the frame without danger of breakage. Other objects will appear as the 25 description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the 35 several views:—

Figure 1 is a broken rear elevation of a frame constructed substantially in accordance with this invention.

Fig. 2 is a vertical section thereof, showing 40 the prop extended.

Fig. 3 is a similar view of the top portion of a frame of a modified construction, and

Fig. 4 is a section on the line IV—IV of 45 Fig. 1.

The frame 1 may be of any suitable configuration and is formed with the groove 2 at its inner rear edge to receive the glass 3 and picture 5. Said glass is held in place 50 by staples 4 having rounded corner bends which insure against breakage and will not mar the picture.

The rear of the frame is covered by a back member 6 of rigid material, preferably cardboard covered both outside and inside with cloth 60, and of substantially

the same size as the frame so as to overlap all of the walls thereof. Said back member is detachably secured to the frame by flexible tongues 7, each having its inner end 60 fastened to the rear of the frame by a nail 8 and adapted to have its outer free end portion bent as at 9 over the edge of the back member as illustrated. When the back 65 is to be removed, said tongues 7 are bent 70 outward, as indicated at the upper right hand corner of Fig. 1.

The back member has a prop 10 hinged thereto by having its upper end portion 12 inserted through a slit 11 in the back member and outer covering 60 thereof and concealed between said back member and the inner covering 60 thereof, said prop being scored at 19 adjacent to the slit so as to permit an easy hinge movement without danger 75 of separating the back member from the frame. This means of securing the prop to the back member is simple, inexpensive and neat in appearance, and produces a smooth finish on both the inner and outer faces of 80 said back member. The prop 10 is stiffened at 16 below the scored line 19, and the portion above said slit and line may also be stiffened at 17, Fig. 2, if desired, or said stiffening may be omitted, as suggested at 85 18 in Fig. 3. When the stiffening 17 is employed, it makes an extra thickness on the inside of the back member which may be advantageous in holding the picture more firmly in place. The prop may be connected 90 to the back member by a ligament 20 to limit the outward swing of said prop.

The back member also carries a hanger loop or ring 13 which is embraced by a staple 14 the prongs of which extend 95 through the outer portion of the back member and are bent over at 15 so as to lie under the inner covering on the inner surface of the back member. In this way the hanger is attached to the back member independently 100 of the frame and may be removed with said back member from the frame. Moreover, only the folded portion of the staple is exposed on the outside of the back member where it presents no objectionable 105 obstruction.

Having thus described my invention, what I claim as new and desire to secure by Letters Patent of the United States is:—

1. The combination with a picture frame, 110 of a rigid back member having an inner layer of material thereon and a slit covered

- by said inner layer, and a rigid prop projecting from the outer surface of the back member and having its upper end portion extending through said slit and concealed 5 between said back member and inner layer.
2. The combination with a picture frame, of a rigid back member having an inner layer of material thereon and a slit covered by said inner layer, and a rigid prop projecting from the outer surface of the back member and having a flexible upper end portion extending through said slit and concealed between said back member and inner layer.
- 10 3. The combination with a picture frame, of a rigid back member having an inner layer of material thereon and a slit covered by said inner layer, a rigid prop projecting from the outer surface of the back member 15 and having its upper end portion extending through said slot and concealed between said back member and inner layer, a hanger loop on the outer surface of the back member, and a staple embracing said loop and 20 having its prongs passed through the back member and also concealed between it and the inner layer above the upper extremity 25 of the prop.
4. The combination with a picture frame 30 having a groove in its inner edge to receive a glass and picture, of staples driven into

the inner edge of the frame in said groove for retaining said glass and picture in place therein, a back member of rigid material having coverings on its inner and outer surfaces, there being a slit in the back member and outer covering thereof, a prop having its upper end portion extending through said slit and concealed between the back member and the inner covering thereof, and 35 means for detachably securing said back member over the groove in the frame.

5. The combination with a picture frame having a groove in its inner edge to receive a glass and picture, of staples driven into 40 the inner edge of the frame in said groove for retaining said glass and picture in place therein, a back member of rigid material having a covering on its inner and outer surfaces, there being a slit in the back mem- 45 ber and outer covering thereof, a prop having its upper end portion extending through said slit and concealed between the back member and inner covering thereof, and flexible tongues secured to the rear face of 50 the frame and adapted to be bent over the edges of the back member for removably securing the same over the groove.

In testimony whereof I have signed my name to this specification.

SIMON WEISS.
